UNITED STATES PATENT OFFICE.

WILLIAM E. SHARPLES, OF FALL RIVER, MASSACHUSETTS.

RACE-BOARD AND REST-BOARD FOR LOOMS.

SPECIFICATION forming part of Letters Patent No. 448,374, dated March 17, 1891.

Application filed May 8, 1890. Serial No. 351,055. (No model.)

To all whom it may concern:

Be it known that I, WILLIAM E. SHARPLES, a citizen of the United States, residing at Fall River, in the county of Bristol and State 5 of Massachusetts, have invented certain new and useful Improvements in Race-Boards and Rest-Boards for Looms; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to looms, and its object is to remedy the defects now inherent in certain parts of the machine, and to thereby improve its operation and cause it to give better results.

20 It is customary to attach to the top of the lay in certain kinds of looms a thin strip of wood along which the shuttle travels and across which the warp is drawn. This strip is known as the "shuttle-race board." The 25 constant friction of the thread as it moves transverse to the path of the shuttle, together with the wear due to the movements of the shuttle itself, tends to make the race-board rough and uneven, so that after a time it will 30 be found full of the transverse grooves and other irregularities. This gives rise to faulty and imperfect work since the warp-threads are caught and broken or prevented from running at the proper intervals apart. The 35 race-board therefore must be frequently renewed at more or less expense and trouble. In the case of the rest-board or breast-beam rod the annoyances due to uneven wear are even more frequent. This rod is usually a

40 strip of wood fastened to the breast-beam of the loom, and it forms the wearing-surface over which the completed fabric is drawn on its way to the sand-roller or cloth-beam. It is absolutely essential that this rod be perfectly smooth, since any roughness in it causes the fabric to pull askew by catching in the filling. When thin gauzy goods—such as mosquito-netting—are being woven, the filling is particularly liable to be pulled out 45 of place as it passes over the rest-board. The wooden strip commonly used quickly wears

into ridges under the friction of the threads, particularly on the selvages, where the greatest strain comes, and requires constant attention and repair to insure an even fabric. 55 My invention entirely obviates the troubles inherent in these wooden breast-beam rods.

In the drawings, Figure 1 is an end elevation of a portion of a loom, showing my improvement in position. Fig. 2 is a cross-section on 60 an enlarged scale of one form of my race-board; and Fig. 3 is a similar section of my rest-board.

The loom may be of any desired style, A representing the frame; B, the picker-stick; 65 C, the lay; D, the race-board; E, the shuttle; F, the warp; G, the rest-board, and II the sand-roller. The race-board D is composed of a thin strip of wood, flat on its top and bottom and beveled on its inner edge d to rest 70 against and hold in place the lower part of the reed I. This is the ordinary construction.

My improvement consists in enveloping it completely in a metallic sheathing d', composed of sheet-tin, zinc, brass, aluminum 75 bronze, or the like, a non-oxidizable metal being preferred. The sheathing lies smoothly across the top of the race-board and is carried entirely around it. It extends continuously from one end of the race to the other, 80 so as to offer a smooth unbroken surface for the passage of the warp-threads and the movement of the shuttle.

The most convenient mode of applying the sheathing to the race-board is to form it into 85 a tube of the proper shape and size and then insert the wooden filling into it. This mode of procedure is adapted to either new or old race-boards.

I am aware that it has been proposed to 90 face race-boards with a strip of steel having a burnished surface. This is costly to make and expensive to repair and renew. My sheet-metal sheathing is cheaper and more easily made and applied. Enveloping the race- 95 board it lies smooth and flat and requires no extra fastening to keep it in place. It can be made of thin material, since it does not depend upon its own stiffness to keep it close to the race-board. Moreover, its thinness enables it to be applied to existing worn race- 100 boards without altering them, the thickness

of the sheathing being so slight as to be immaterial.

The rest-board G is usually made of hard wood with rounded edges. This I provide with a sheathing *g* of thin sheet metal, preferably tin-plate. The sheathing is tubular, so as to completely inclose the rest-board, and the meeting edges of the sheet metal may be united by a seam *g'*, or in any other suitable manner. As in the case of the race-board, the sheathing is equally well applicable to old or new rest-boards. It extends the entire length of the board and affords a smooth unbroken surface for the cloth to draw over. The filling which passes it parallel with its length finds nothing to prevent the easy movement of each thread across the polished surface of the metal, so that the most delicate and flimsy stuff can be drawn over it without any danger of its threads being disarranged. Furthermore, my improvements enable the loom to do better work and lessen the breakages of warp-threads. The cost of repairs is reduced, and they do not have to be made so frequently.

I am aware that the lease-rods which separate the warp-threads before they reach the harness have been covered with metal to reduce their wear; but the reduction of wear is not all that I accomplish by sheathing my

rest-board with metal. It serves the further purpose, as set forth above, of presenting a smooth and even surface for the cloth to pass over after it is woven, thereby preventing damage to the cloth, and especially to thin gauzy fabrics by the pulling askew of the filling. This is a very important result, and one that cannot be brought about by covering the lease-rods with metal.

Having thus described my invention, what I claim, and desire to secure by Letters Patent, is—

1. A race-board for looms, composed of a strip of wood having a continuous tubular close-fitting sheathing of sheet metal applied thereto, substantially as described.

2. A rest-board for looms, composed of a strip of wood enveloped in a continuous sheathing of sheet metal, substantially as described.

3. The combination, with the wooden rest-board G, of the sheet-metal sheathing *g*, having its edges seamed together, substantially as described.

In testimony whereof I affix my signature in presence of two witnesses.

WILLIAM E. SHARPLES.
